UNITED STATES PATENT OFFICE.

FRED SHAW, OF MIDDLETON, AND JOSEPH DUTTON, OF HALE, ENGLAND.

APPARATUS FOR RAISING PILE FABRICS.

1,096,062.

Specification of Letters Patent.

Patented May 12, 1914.

Application filed December 13, 1913. Serial No. 806,451.

To all whom it may concern:

Be it known that we, FRED SHAW and JOSEPH DUTTON, both subjects of the King of Great Britain, and residing, respectively, 5 at 14 Durnford street, Middleton, in the county of Lancaster, and Wyke House, Wингate Road, Hale, in the county of Chester, both in the country of England, have invented certain new and useful Improvements 10 in Apparatus for Raising Pile Fabrics, of which the following is a specification.

This invention relates to cross brushing machines for raising pile fabrics such for 15 example as velvets, cords and the like, and has for its chief object to increase the efficiency and output of apparatus of this class.

In cross brushing machines as at present 20 constructed it is customary to employ a number of rows of rollers arranged one above the other, the upper row or rows of rollers constituting the brushing rollers and the lower row the tensioning rollers the 25 fabric to be treated being traversed in a zigzag fashion over the brushing rollers and under the tensioning rollers, and subjected to a brushing operation by a reciprocating brush which travels to and fro across the 30 width of the fabric, one brush being employed in conjunction with each brushing roller. This arrangement necessitates a large number of working parts and a machine which covers a considerable amount 35 of floor space, moreover a large amount of power is required to draw the fabric under and over the various sets of rollers.

According to this invention instead of 40 applying a single brush to each brushing roller and employing a number of such rollers to complete the brushing operation, the fabric to be treated is traversed around a revolving drum and is subjected to a reciprocating brushing action in a lateral direction 45 by relative movement of the fabric and a series of brushes which surround or partly surround the drum. The latter may be made of such a diameter as to accommodate a sufficient number of brushes to complete the 50 brushing operation on one drum. Two or more of such drums may be placed one above the other in one machine and two or more pieces of fabric may be treated at the same time, or if desired the drums may be made 55 somewhat smaller in diameter and the fabric may be taken from one drum to another to

complete the brushing operation. The aforesaid relative movement of the fabric and brushes is advantageously produced by imparting a reciprocating endwise movement 60 to the drum and holding the brushes which surround the same in a stationary condition, any suitable means being provided for causing the brushes to exert pressure upon the fabric and for taking up for wear in the 65 bristles.

In the accompanying drawings: Figure 1 is a front elevation and Fig. 2 an end elevation of a machine provided with two drums in accordance with this invention. 70 Figs. 3 and 4 are diagrams of the brushes. Fig. 5 is an end view of the drum around which the brushes are arranged. Fig. 6 is a longitudinal section of part of the drum. Fig. 7 is a detached view showing the parts 75 of the mechanism which exert a resilient pressure upon the backs of the brushes, and Fig. 8 is a detached view of one of the brush holder end frames.

A indicates the revolving drum and B B 80 indicate the brushes. Each of the brushes B is supported at each end in a frame or holder b that is formed with a number of pockets b¹ (Fig. 5) to receive the ends of the brush backs and is secured to the adjacent end frame C of the machine. The brushes are detachably mounted in the aforesaid pockets and the ends of each brush back are rabbeted or recessed at b² (Figs. 3 and 4) to enable the brushes to be adjusted for 85 wear and to prevent the brush back from coming into contact with the fabric, the arrangement being such that before the bristles are worn flush with the surface of the brush the portion b³ of the brush back 90 comes into contact with the pocket flange b⁴ (Fig. 8) and prevents further adjustment of the brush. Each brush is arranged to exert a yielding pressure upon the fabric by means of springs provided with regulating 95 devices for controlling the pressure exerted by the springs. Any appropriate mechanical device may be employed for effecting this purpose and in the example shown spring controlled levers b⁵ are pivoted on studs b⁶ 100 carried by brackets b⁷ that are fixed to the brush holder frames b and each lever is attached to one end of a torsion spring b⁸ that is connected at its opposite end to a collar b⁹ supported on the stud b⁶ and secured 105 thereto by a pin b¹⁰. This collar may be formed with a number of radial holes for

the reception of the aforesaid pin so that the collar may be turned in either direction through a revolution or portion of a revolution and secured in its adjusted position by 5 the pin to slacken or tighten the spring according to the pressure to be exerted by the levers b^5 upon the brush back.

In an alternative arrangement a blade 10 spring extending along the brush back and provided with screw adjustment may be substituted for the device described. In the example shown the bristles B of the brushes are inserted in spaced rows as shown in Fig. 3 a row of bristles in one brush coming opposite to a blank portion in the adjacent brush and each blank portion is formed with an aperture b^{11} for allowing the escape of flock and lint. This construction is not however absolutely necessary and the bristles 15 may be otherwise arranged and the holes b^{11} be dispensed with. In the example shown in the drawings two of the rotary drums A are placed one above the other and each of these drums is reciprocated in an 20 endwise direction while the brushes B remain stationary. For this purpose each of the drums is slidably mounted upon a square shaft a (Figs. 5 and 6) rotatably mounted in bearings a^1 (Fig. 2) on the end frame C. 25 These shafts are connected by a belt on the pulleys a^2 (Fig. 1) and receive their motion from a main driving pulley a^3 on a shaft a^4 and stepped speed cones a^5 a^6 . Endwise motion is imparted to the drums A by a 30 lever a^7 pivoted in a bracket a^8 carried by the end frame C. This lever is slotted at a^9 for the passage of the drum shafts and is connected by links a^{11} with a collar a^{12} (Figs. 5 and 6) rotatably mounted on a 35 bush a^{13} which supports the end of the drum A upon the square shaft. The collar a^{12} is retained in position by a plate a^{14} screwed to the drum A. The upper end of the lever is connected by a rod a^{15} (Fig. 1) with a 40 cranked portion of a shaft a^{16} driven by bevel gearing a^{17} from a shaft a^{18} which is connected with the main driving shaft a^4 by a belt on the pulleys a^{19} (Fig. 1). In order to cause the fabric to follow the movement 45 of the drum the latter is formed or provided with a roughened or other appropriate surface which will prevent the fabric from slipping thereon, for example it may be covered with a material resembling card 50 clothing which is used in ordinary cotton carding engines, but with the teeth of the wire pins projecting above the surface of the clothing to a sufficient extent to engage with and grip the adjacent surface of the 55 fabric as it is passed through the machine.

In order to prevent the fabric from creasing longitudinally through the reciprocating

movement that is imparted thereto in a lateral direction the fabric is fed to the drum through a group of rollers D. These 65 rollers are carried between end frames d (Figs. 1 and 2) which are slidably mounted upon a square shaft d^1 carried by brackets d^2 (Fig. 1) secured to the machine frame C and each end frame d at one end of the machine is connected by a link d^3 with an arm 70 projecting from the aforesaid lever a^7 so that the movement of the latter causes each group of rollers to move in an endwise direction with its drum. The aforesaid group 75 of rollers in addition to preventing the aforesaid longitudinal creasing of the fabric also serve to retain the fabric in contact with the surface of the drum. The fabric after being treated by the lower drum may 80 be taken to the upper drum to have the brushing operation completed and in this case the upper drum may be rotated slightly faster than the lower drum to maintain a tension upon the fabric, or if desired a separate piece of fabric may be treated by each 85 drum. When the fabric is taken from one drum to the other, the two drums reciprocating in opposite directions alternately stretch the fabric in opposite directions 90 diagonally and open the pile in a lateral direction and so put the fabric in a better condition for being acted upon by the brushes.

Claims:

1. In a cross brushing machine, the combination, with a revoluble drum for supporting and traversing the fabric to be brushed, of brushes arranged around the said drum, springs which press the brushes against the fabric while on the drum, and 100 means for reciprocating the drum and the fabric endwise of the drum.

2. In a cross brushing machine, a rotary drum around which the fabric to be treated is traversed, a series of stationary brushes 105 spaced around the drum and means for imparting an endwise reciprocating motion to the drum.

3. In a cross brushing machine, a rotary drum around which the fabric to be treated 110 is traversed, a series of stationary brushes spaced around the drum, a group of rollers through which the fabric is fed to the drum, and means for imparting an endwise reciprocating motion to the drum and to the 115 group of rollers.

In testimony whereof we affix our signatures in presence of two witnesses.

FRED SHAW.
JOSEPH DUTTON.
